COMBINED BENCH AND STORAGE CHEST

James F. Curtin, 16044 E. Queenside Drive,
Covina, Calif. 91722

Filed Oct. 2, 1974, Ser. No. 511,168

Term of patent 14 years

Int. Cl. D6—01, 04

U.S. Cl. D6—64

FIG. 1.

FIG. 2.

FIG. 3.

FIG. 1 is a front, top and left side perspective view of a combined bench and storage chest showing my new design;

FIG. 2 is a rear elevational view; and

FIG. 3 is a bottom plan view.

I claim:

The ornamental design for a combined bench and storage chest, as shown.
